THEATRICAL AMUSEMENT, EDUCATIONAL, AND ADVERTISING DEVICE

Filed March 29, 1921

Fig. 1,

Fig. 2,

Fig. 3,

UNITED STATES PATENT OFFICE.

WILLIAM F. POWERS, OF ENGLEWOOD, NEW JERSEY.

THEATRICAL AMUSEMENT, EDUCATIONAL, AND ADVERTISING DEVICE.

Application filed March 29, 1921. Serial No. 456,506.

To all whom it may concern:

Be it known that I, WILLIAM F. POWERS, a citizen of the United States, residing in Englewood, county of Bergen, and State of New Jersey, have invented the following new and useful Improvements in Theatrical Amusement, Educational, and Advertising Devices.

My invention relates to a modification or improvement of the combination, fully set forth and claimed in my application executed March 24, 1921, of a phonograph record and a miniature knock-down, theatrical stage setting, together with movable or adjustable actor-figures therefor, said stage setting and actor-figures bearing pictorial representations, designs or other insignia corresponding to the words and action of the phonograph record and being made of cardboard of such size and contour as to be capable of compact assembly flatwise with the record in a package of substantially the dimensions now commonly used for the sale and shipment of records, so that the purchaser of such a package can unfold or assemble the stage setting and use the same and the movable actor figures in demonstration or illustration of the subject of the record to which said setting refers. I am of course aware that miniature stage mechanism and actor figures have heretofore been made and sold, but so far as I am aware no one has previously proposed to make and correlate such mechanism with a particular theme of a phonograph record and combine the same with its said record in compact commercial package form so as to make thereof a combination that constitutes a sales commodity having educational, recreational and advertisement advantages as above mentioned, and in which the stage setting has a stiffening effect and serves, as to a certain extent the figures do also, as a protection to the record.

The invention of this application like that of my aforesaid application is an amusement, educational and advertising device, but differs therefrom in that the miniature knock down stage setting is adapted to serve when flat as a container for the phonograph record and if desired for the actor figures, all of which cooperate as before in the dramatic interpretation of the record.

The present application is thus largely concerned with such a miniature knock-

down theatrical stage setting adapted as stated to act as a container for a phonograph record and also with the construction of the knock-down stage setting itself specifically and in a broader sense, and with the combination of the stage setting and the record for which it acts as container and of these with the actor figures.

Referring to the drawings: Figure 1 is a perspective view of the stage setting folded flat or in knock-down position and showing a phonograph record contained therein; Figure 2 is a plan of the blank for the stage setting, and Figure 3 is a perspective view showing the stage setting set up in position for use with actor figures thereon.

The stage setting and in particular the back drop may be illustrated artistically in any appropriate way so as to be suggestive of the theme or subject matter of the record for which it acts as container and the range of themes or subject matter of the records chosen may be indefinitely varied through the realms of song, story and other literature and music. Indeed the field from which the maker of the phonograph records may select themes for records is by this invention enlarged, since their visual portrayal makes attractive and salable records of subjects—such for instance as bird calls and Bible stories—not otherwise sufficiently interesting to command a ready market. Such artistic matter may be specific or general and is often the latter since records are usually double. A perfectly plain background, or one merely decorative, is lacking in interest. In the present instance Robinson Crusoe is the story told by the record, and the back drop 2 bears artistic matter suggestive of this theme. The actor figures shown on the stage in Figure 3 will be recognized as representations of Robinson Crusoe, Friday and a cannibal. Various other actor figures such as Robinson Crusoe as a boy, the ship captain, sailors, natives of eastern countries, etc., could also be used. This ancient favorite with its perennial, age old appeal to children may thus be enacted by the child himself, who shares in Robinson Crusoe's varied emotions and experiences, or by some interested older person. Both instruction and entertainment inhere in this well directed literary and dramatic play.

100

110

In describing the miniature stage setting, I have used the word "knock-down," meaning by this term to include both structures in which the parts of the stage setting are 5 separate and may be assembled, and structures such as that illustrated in the drawings, in which the stage setting is flat or capable of being folded flat, or into set-up position. The stage setting has a front 10 member 1 constituting the stage arch and containing the stage opening and a back drop 2, parallel scoring lines enabling the blank to be folded to form an accordion hinge or folding connection 3 between the 15 two parts. The front member 1 may be provided with flaps 4 and 5, which may be cut out along the edges which are designed in use to be free, or may be left as a continuous part of the said member, lines being 20 provided to indicate where the flaps should be cut or bent. These flaps before they are folded occupy the stage opening, at least in part. They are illustrated as designed to be folded respectively about the 25 top and the bottom edges of the stage opening, each flap may be provided with a scoring line 6 parallel with its free edge in order to permit the free end of each flap to be bent, these bent portions or supplemental 30 flaps 7 and 8 respectively being adapted one to form the support for the stage proper or platform which the flap 5 constitutes when the stage setting is in set up position, and the other to assist in keeping in place 35 the stage top which is constituted by the flap 4 when in set up position. Both the members 1 and 2 are provided with flaps for retaining the record in place and means for releasably connecting said front and back 40 members are also provided. While of course the construction need not be just as illustrated, it is shown as follows: The member 1 is provided with a flap 9 at one side thereof, which flap is folded or designed to 45 be folded on the scoring line 10. This flap is provided with a pair of what may be described as hinge lugs 11, since they are arranged like pairs of hinge pintles. These lugs are beveled as shown to facilitate their 50 cooperation with a pair of slots 12 near the edge of the back member 2, the arrangement being such that the lugs 11 may be passed through the slots which are long enough to permit this and then be moved endwise in 55 the slots until the neck portions 13 are pushed home against the bottoms of the slots 12. A separable and a locking connection is thus provided when the stage setting is in set up position, as indicated in Figure 3. 60 These lugs or slots perform a further function since they constitute releasable connecting and locking means which may be brought into play when the stage setting is in flat or knock-down condition. This 65 connection may be effected by folding the

flap 9 over the edge of the back member 2 and behind it and by pushing the lugs through the slots and then moving them endwise to lock in a manner substantially like that above explained. The accordion hinge and the flap 9 constitute, when the parts are in knock-down position, means for preventing the record 14 from sliding out at the sides of the container formed by the stage setting. To prevent the record from sliding out at the top or bottom, flaps 15 and 16 folded or foldable on the scoring lines 17 and 18 are provided, these flaps being shown as located on the back member 2. The flap 15 may also serve as a top for the stage. The stiffening and record protecting effect of the stage setting when acting as container is evident.

It will be apparent that the record might be shipped in the stage setting without the use of any outer receptacle, although to avoid soiling the stage setting I prefer to enclose it in an outer envelope, the package being in either case of substantially the dimensions now commonly used for the sale and shipment of phonograph records and constituting a sales commodity having educational, recreational and advertisement advantages.

The actor figures as in my aforesaid application may be cut outs or adapted to be cut out, if for commercial reasons or to provide further amusement to the child in cutting them out, this is considered desirable. Of course they need not be placed in the container constituted by the stage setting, although where they are already cut out this is convenient. The use of the stage setting as a container for the record during shipment is very advantageous.

The artistic background being so placed on the stage setting as to be on the inside of the container when closed or flat is in this way protected and the fact that the stage opening is then closed makes the protection complete.

The stage setting with the actor-figures constitute a visualizer or dramatizer for the phonograph record on which is recorded for audible indication thereby subject matter susceptible of dramatic representation or illustration, to which the appearance of the stage setting is appropriate and of which the actor figures are illustrative.

Claims:

1. The combination of a phonograph record, actor-figures bearing pictorial representations, designs or other insignia corresponding to the words and action of the phonograph record, and a phonograph record container capable of re-arrangement as a stage setting, adapted to be shipped flat with the record within it, having record retaining means constituting it when in that condition, a container for the record, and

having members cooperating to sustain the record container in position for use as a stage setting.

2. An amusement, educational and advertising device comprising in combination in compact commercial package form as a sales commodity, a phonograph record, a miniature knock-down theatrical stage setting, and movable or adjustable actor figures, said stage setting and actor figures bearing pictorial representations, designs or other insignia corresponding to the words and action of the phonograph record and being made of cardboard of such size and contour as to be capable of compact assembly flat-wise with the record in a package of substantially the dimensions now commonly used for the sale and shipment of records, and being so assembled with the record with in the stage setting which to that end is provided with phonograph record retaining means.

3. The combination of a phonograph record with a cardboard structure serving both as a phonograph record container and as a stage setting and having front and rear members flexibly connected along one edge, and provided with record retaining means adjacent at least two other edges preventing the record from sliding out of the container, the front member providing a stage opening, and means for spacing the part of the back member opposed to the stage opening at a distance in rear thereof and for maintaining it in that position to provide stage space.

4. A miniature theatrical stage setting having front and back members provided with means for retaining between them when flat a phonograph record so that they then constitute a phonograph record container, releasable locking means for securing said members together, and means for spacing them apart from front to rear in position of use as a stage setting, wherein they assist in supporting each other, the said releasable locking means also securing said members together in set-up position.

5. The combination of a phonograph record with a miniature knock-down theatrical stage setting of the folding type adapted to be shipped flat with the record and to constitute when in that condition a container for the record, said stage setting having front and rear members co-operating and supporting each other in set-up position and presenting a stage opening and stage space and between which when the stage setting is in knock-down position, said record is received, and flaps for retaining it in position within the knocked down stage setting.

6. The combination of a phonograph record with a miniature knock-down theatrical stage setting of the folding type adapted to be shipped flat with the record and to con-

stitute when in that condition a container for the record, said stage setting having front and rear members hinged together along adjacent edges and between which said record is received, and flaps closing other edges of the container formed by the stage setting when it is in flat or record holding position, and releasable means for securing the members together in set-up position.

7. The combination of a phonograph record with a miniature knock-down theatrical stage setting of the folding type adapted to be shipped flat with the record within it and having means constituting it when in that condition a container for the record, said stage setting having front and rear members between which said record is received, and releasable means for locking the members together both in knock-down and in set-up position.

8. The combination of a phonograph record, and a miniature knock-down theatrical stage setting adapted to be shipped flat with the record within it and having means constituting it when in that condition a container for the record and capable of rearrangement into position for use as a stage setting, said stage setting comprising front and rear members hinged together and between which when folded said record is adapted to be received, said stage setting having foldable flaps serving to retain the record in position between the folded members of the stage setting, and members of the stage setting.

9. The combination of a phonograph record and a miniature knock-down theatrical stage setting adapted to be shipped flat with the record and to constitute when in that condition a container for the record and to be set up for use, said stage setting comprising front and rear members hinged together and between which when folded said record is adapted to be received, said stage setting having foldable flaps serving to retain the record in position between the folded members of the stage setting, and releasable means for securing said members together in their flat record containing position.

10. The combination of a phonograph record, actor figures bearing pictorial representations, designs or other insignia corresponding to the words and action of the phonograph record, and a phonograph record container capable of re-arrangement as a stage setting, adapted to be shipped flat with the record within it, having record retaining means constituting it when in that condition, a container for the record, having a stage platform member for the actor figures, and having members cooperating to sustain the record container in position for use as a stage setting with the stage platform members substantially horizontal.

11. In a miniature knock-down theatrical stage setting a front member providing the stage arch and containing the stage opening and having a flap occupying originally part 5 of the stage opening foldable inward around an edge of said opening to constitute the stage proper or platform when the stage setting is in set up position and having a supplemental foldable flap to assist in supporting the platform. 10
12. In a miniature knock-down theatrical stage setting a front member providing the stage arch and containing the stage opening and flaps occupying originally part of the 15 stage opening foldable inward respectively around the top and the bottom edge of said opening to constitute respectively the top of the stage space and the stage proper or platform when the stage setting is in set-up 20 position.
13. In a miniature knock-down theatrical stage setting a front member providing the stage arch and containing the stage opening and having flaps occupying originally part of the stage opening foldable respectively around the top and the bottom edge of said opening to constitute respectively the top of the stage space and the stage proper or platform when the stage 25 setting is in set-up position and having supplemental flaps to assist in supporting said top and said platform. 30
14. A cardboard structure serving both as a phonograph record container having record retaining means and as a stage setting provided with a stage opening and having adjacent front and rear members having mutually opposed inner front and rear surfaces in substantially the same plane adapting it to be shipped flat and having also means for supporting the stage setting structure with the part of its back member behind the stage opening spaced to the rear thereof to provide stage space. 35
15. A miniature theatrical stage setting having connected front and back members having opposed inner surfaces and occupying substantially the same plane during shipment, and capable of rearrangement in 40 set-up position ready for use as a stage setting, the front member being provided with a stage opening obstructed by the material of the front member during shipment and the back member having on its front or inner side artistic matter thus located on the inside and protected when the stage setting is flat but visible through the stage opening as a background when the stage opening 45 has been freed from obstructing material and the stage setting is set-up, and means for spacing and maintaining the part of the 50 back member opposed to the stage opening a distance in the rear thereof to provide stage space. 55
16. A miniature theatrical stage setting 60 provided with flexibly connected front and back members having mutually opposed adjacent inner surfaces adapting it to be shipped flat and having record retaining folds constituting it when in that condition 65 a container for a phonograph record, the front of the back member being decorated and the decorations being thus so placed on the stage setting as to be on the inside of the container when it is flat. 70
17. A cardboard structure serving both as a phonograph record container having record retaining folds and as a stage setting and comprising front and back members connected by a flexible fold along one side 75 and foldable into set-up position spaced apart from front to rear in readiness for use or into substantially the same plane in mutual opposition for shipment, said members constituting means for supporting the stage setting in set-up position. 80
18. A miniature stage setting capable of occupying a flat position and having a front member provided with a stage opening closed when the stage setting is in that position, and a back member connected to said front member at one side thereof, said members having means for retaining them in flat position and for keeping a phonograph record in place in the flat stage setting behind the closed stage opening, the inner surface of said back member bearing artistic matter illustrative of the theme of said record, and means for supporting the stage setting in set-up position with the inner surface of the back member visible through the stage opening then unobstructed, so as to constitute a background appropriate to the theme of the record. 90
19. A miniature theatrical stage setting 95 having connected front and back members one of which has a stage opening and which have opposed inner surfaces said stage setting being adapted to be shipped flat with its material obstructing the stage opening 100 and to constitute when in this condition a container for a phonograph record and having on its inside opposite said obstructed opening artistic matter protected during shipment by said material and constituting 105 when the stage setting is set up and the stage opening freed from obstruction a background visible through the stage opening. 110

In testimony whereof, I have signed this 120 specification.

WILLIAM F. POWERS.
